(57) **CLAIM**

The ornamental design for a diagnostic device, as shown and
described.

DESCRIPTION

FIG. 1 is a perspective view of a diagnostic device showing
our new design;

FIG. 2 is a front side elevational view of the diagnostic
device of FIG. 1;

FIG. 3 is a rear side elevational view of the diagnostic device
of FIG. 1;

FIG. 4 is a left side elevational view of the diagnostic device
of FIG. 1;

FIG. 5 is a right side elevational view of the diagnostic device
of FIG. 1;

FIG. 6 is a top plan view of the diagnostic device of FIG. 1;
and,

FIG. 7 is a bottom plan view of the diagnostic device of FIG.
1.

The broken lines shown in the drawings illustrate portions of
the diagnostic device that form no part of the claimed
design.

The broken lines form no part of the claimed design.
